UNITED STATES PATENT OFFICE

HARRY B. WHITE, OF CANTON, OHIO, ASSIGNOR TO THE HOOVER COMPANY, A CORPORATION OF OHIO

SUCTION CLEANER AGITATOR

Application filed January 2, 1929. Serial No. 329,866.

This invention relates to suction cleaner rotors or agitators of the rotary type which are adapted to be mounted in suction cleaner nozzles.

5 Heretofore agitators have necessarily been of a large diameter because of the impossibility in die casting of removing the small core from a single piece agitator body of small diameter and the failure to obtain satisfactory 10 commercial results from multiple unit body construction. It has also been the experience heretofore that satisfactory small diameter agitators could not be constructed due to the fact that the countersunk brush seats are limited 15 in their approach to the rotor center by the bearing shaft extending therethrough which has of necessity been used in the past in order to secure correct centering of the rotor. No compromise in the depth of the 20 brush seat is possible in the well designed agitator because of the necessity of long bristles in order to secure the requisite strength and flexibility. The problem of eliminating the bearing shaft within the rotor and still 25 obtain satisfactory bearing means therefor is for the first time successfully solved in the present invention through the use of novel means.

The use of a large diameter agitator necessitates a large nozzle and a consequent large nozzle opening into which the carpet or article being cleaned, when the machine is in operation, is drawn with a resulting great resistance to movement of the machine there- 30 over. By the use of a small diameter agitator, such as can be satisfactorily constructed in accordance with this invention, the nozzle dimensions can be greatly reduced resulting 35 in a decrease in the covering area drawn into the nozzle and a consequent desirable reduction in the resistance to movement of the machine. As the cleaning action in a suction cleaner takes place over a limited area only 40 of the nozzle opening and as the decrease of the width thereof would have no detrimental effect upon the cleaner efficiency, the desirability of a relatively small nozzle is apparent 45 and as the agitator dimensions determine the nozzle dimensions the desirability of a small 50

agitator which can be built commercially is obvious.

The object of my invention is, therefore, the provision of a suction cleaner agitator having all the desirable features of a relatively 55 large agitator yet which in itself is of a small diameter. A further object of my invention is to provide a small diameter agitator for suction cleaners which is designed and constructed so that its small diameter 60 does not prevent its manufacture by ordinary manufacturing methods such as die casting. Other objects and advantages will be apparent 65 as the description proceeds.

In the drawings accompanying and forming 65 a part of this application in which is illustrated a preferred embodiment of my invention:

Figure 1 is a view partly in cross section through my invention disclosing the parts in 70 assembled relation.

Figure 2 is a transverse cross section on the line A—A of Figure 1 with the bearing removed.

Figure 3 is a transverse cross section on the 75 line B—B of Figure 1.

Figure 4 is a transverse cross section on the line C—C of Figure 1.

In the drawings, like parts are indicated 80 by the same reference characters throughout.

In accordance with my invention the agitator is composed of a plurality of individual complementary members forming in their assembled relation, a symmetrical whole. Referring to Figure 1 reference characters 2 and 35 3 indicate the two members forming the body of the agitator indicated generally by the reference character 1. In the assembled relation the body 1 is cylindrical and has a brush seat at each side of the longitudinal center 90 line, which are diametrically opposed. The brush seats are indicated by the reference character 7 and half of each brush seat is carried by each of the members 2 and 3 being formed of reentrant wall-portions. Securing means 6 pass through each of the members 2 and 3 along the greatest diameter and, as is clearly seen in Figure 2, extend parallel 95 to the bottom face of the brush seat 7 and extend slightly into this brush seat. The se- 100

curing means 6 of the members 2 and 3 are counter-sunk as at 4 so that a smooth surface is presented on the cylindrical agitator body. At the approximate longitudinal center of the members 2 and 3 convexly curved surfaces 5-5 are formed, which cooperate in the assembled relation of the body member 1 to form a pulley 10 adapted to receive a driving belt. Beater elements 9-9 are attached to the 10 surface of the members 2 and 3 as in the usual agitator and are shown extending spirally therearound. Semi-cylindrical walls 11-11 parallel to the longitudinal axis extend from the ends of the body members 2 and 3 and form in the assembled 15 relation a cylindrical housing adapted to receive an end plate 12 carrying the bearing support 20 for that end of the agitator. A stud 14, located centrally of each end plate 20 and extending in the opposite direction from said stub shafts or bearing supports 20, cooperates with a receiving bore 15 in the end of the agitator to correctly position the end plate 12. Screws 16-16 pass through the 25 end plates into the end of the agitator body and secure said end plates in place. An end member 17 encloses and is fixedly attached to a bearing composed of a ball race member 18 with balls 19 therein and an inner race member 13 which is non-rotatably mounted on the agitator bearing support 20 extending therein. In the operation of the agitator in a suction 30 cleaner, the member 17 is held rigidly against the suction cleaner frame, the agitator is supported in position through the members 18 and 20, balls 19 and bearing support member 20 at each end of the agitator.

It is seen from the foregoing description that I have provided an agitator having the 40 desirable features of the modern agitator and which because of its novel design includes no small diameter hollow members from which a core must be drawn longitudinally in die casting and which therefore permits of construction in relatively small sizes commercially. The main body members 2 and 3 being split longitudinally and presenting open 45 surfaces through which the core may be drawn in casting cooperate in the assembled relation to produce an agitator having the same strength and effectiveness that has heretofore been possible only in one piece agitator 50 constructions.

I claim:

55 1. An agitator for suction cleaners characterized by the fact that said agitator comprises a plurality of complementary members forming a body, said members having cooperative reentrant portions forming in 60 their assembled relation brush seats and brushes positioned in said brush seats.

2. An agitator for suction cleaners characterized by the fact that said agitator comprises two connected members forming a 65 body, said members having reentrant portions

at each end of the body, said reentrant portions being on opposite sides of the axis of the body, said reentrant portions cooperating to form brush seats in their assembled relation and brushes positioned in said brush 70 seats.

3. An agitator for suction cleaners characterized by the fact that said agitator comprises two cooperating semi-cylindrical members forming a body, said members having re- 75 entrant portions forming brush seats within the periphery of said body, brushes positioned in said brush seats, and means securing said members in position, said means comprising rivets extending on a diameter 80 of said agitator perpendicular to the plane of contact of said cooperating members and having heads counter-sunk in said agitator.

4. An agitator for a suction cleaner comprising a hollow cylindrical body, said body formed of semi-cylindrical portions extending the length of said body, a longitudinal brush seat formed in said body and within the periphery thereof by cooperating reentrant walls in said portions, a brush positioned in said brush seat, a pulley on said body formed by opposed uninterrupted surfaces on said portions and means at the ends of said portions to rotatably support said agitator about an axis passing thru said brush 95 seats.

5. An agitator for a suction cleaner comprising a hollow cylindrical body, said body formed of semi-cylindrical portions extending the length of said body, a brush seat 100 formed in said body within the periphery thereof and extending inwardly to its center, a pulley on said body between the ends thereof, supporting stub shafts at the opposite ends 105 of said body, and means supporting said stub shafts on said hollow cylindrical body in positive alinement.

Signed at North Canton, in the county of Stark and State of Ohio, this 21st day of December, A. D. 1928.

HARRY B. WHITE.
